UNITED STATES PATENT OFFICE

THOMAS GRISWOLD, JR., OF MIDLAND, MICHIGAN, ASSIGNOR TO THE DOW CHEMICAL COMPANY, OF MIDLAND, MICHIGAN, A CORPORATION OF MICHIGAN

PRESSURE-RELIEVING METHOD AND APPARATUS FOR AUTOCLAVES AND THE LIKE

Application filed September 26, 1925. Serial No. 58,804.

In the practical conduct of the treatment of fluids where it is required to release fluid from a high to a lower pressure, difficulty is experienced with the release or throttling device or valve, which may be used. Particularly is this true if the drop in pressure through the valve is great and also if the fluid is hot or carries abrading material in suspension. The difficulty is one of corrosion or pitting, scouring, cutting, etc. of the valve and valve seat destroying same, interfering with the pressure reducing control and requiring renewals of valves or parts, which, in some cases, are very expensive. In certain cases the volume of fluid flow may be very small and an attempt to throttle such a flow may be likened to an attempt to wire draw a leak. This is a very difficult thing to do successfully, particularly with high pressures and high temperatures.

The object of the present invention is to provide a method of throttling a fluid stream so as to reduce the drop in pressure of the current through a control orifice and in this way materially reduce, if not entirely eliminate, the destructive action of such stream or current on the control valve and associated parts.

To the accomplishment of the foregoing and related ends, the invention, then, consists of the steps and means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

40 In said annexed drawing:—

Fig. 1 illustrates one form of apparatus adapted for carrying out my present improved method, such apparatus being shown as interposed between a typical autoclave and a vessel into which the contents of such autoclave require to be discharged; Fig. 2 is a sectional view, on a somewhat larger scale, of a modified form of apparatus designed for use in a similar connection; and Fig. 3 illustrates diagrammatically a layout of pres-

sure relieving elements arranged to form a system whereby the pressure of a fluid at elevated temperatures and subject to vaporization may be reduced in whole or in part at the temperatures involved and whereby the release of such fluid may be effected at varying rates.

Fig. 1 illustrates a simple application of the present improved method and a corresponding simple form of apparatus, the latter being designed to discharge the contents of an autoclave 1 into a receiving tank 2. The fluid is relieved and led from the autoclave by way of pipe 3 through a control valve 4 and a long pipe or expansion coil 5. A second valve 6 may be placed between the coil and the receiver 2 and the latter will desirably be provided with a vent 7 and a valve controlled outlet 8. Associated with control valve 4 is a pressure gauge 9 for indicating the pressure of the fluid in the autoclave.

The bore of pipe 5 and its length are chosen to suit the requirements in hand in such a way that the friction of the fluid in passing through such pipe is sufficient to retard its velocity and restrict the volume of flow to the desired amount subject to some control of valve 4. Where the fluid is discharged directly from such valve into the receiver 2, the pressure drop across the valve would be approximately equal to the difference between the pressure in the latter and that in autoclave 1, and in some cases such difference is so great as to make it practically impossible to control the discharge by a valve or, at any rate, the use of a valve is both expensive and laborious because it has to be operated with a very small opening through which the fluid escapes at a very high velocity, producing scouring, pitting and cutting.

The effect of the coil or tube 5, however, is to absorb this pressure change and permit such control valve to be operated in a more open position and hence with a wider range of operative throttling movement. If the pressure reducing coil is of sufficient capacity, such valve may be operated practically wide open, while if scour occurs in the pressure reducing pipe so as to decrease its fric-

tional resistance and thereby lower the drop in pressure for the desired flow, the valve 4 will begin to close and function to maintain the pressure at such a point as may be desired, and to this end, such valve may be made to operate automatically by any of several well known methods.

It is permissible to place the control valve in the position of valve 6 (shown as a manually controlled valve) or to have both valves 10 operate automatically.

If a very long or conduit tube is required in order adequately to reduce the pressure, it will be conveniently coiled into a small 15 bulk, as indicated in Fig. 1, and in place of such tube, a labyrinthine conduit or equivalent device, such as illustrated in Fig. 2, may be employed. This modified device comprises a tube 10 in which is placed a series of 20 balls 11 or equivalent obstructions that nearly fill the bore of the tube and so are adapted intermittently to restrict the flow of a fluid through said tube while at the same time providing between the successive constrictions 25 room for expansion or retarding of flow.

In the case of the simple arrangement of apparatus illustrated in Fig. 1, it will be understood that the tube 10 will be substituted for the pipe 5, and it will be noted that in the 30 form shown in Fig. 2, the flow through said tube is from left to right, the balls 11 being held therein by means of a screen 12 adjacent the discharge end.

As previously indicated, in Fig. 3 is shown 35 a modified arrangement of apparatus adapted to reduce pressure of fluids at elevated temperatures and subject to vaporization in whole or in part at the temperatures involved. This apparatus also provides a modified 40 method of controlling the release of such fluids or of any fluids at varying rates as may be desired.

The processed or treated fluid under pressure and at an elevated temperature is designed to enter the system through the supply pipe or line 15 whence it passes through the header 16 in one or the other of a plurality of branches 17 that lead therefrom to a second header 18. Included in each such branch 50 17 is a throttle valve 19 that is protected on either side by a stop valve 20. In operation, but one or at least less than all of the valves in said branches are open to flow at one time, the others being held in reserve. When any 55 particular branch 17 is to be put into use, it is desirable first to open the stop valves at either side of the particular throttle valve concerned and then to control the rate of flow as may be required with such throttle valve only, thus 60 leaving the stop valves undamaged for use in entirely checking the flow when desired since this might be impossible with the throttle valve alone due to wear or cutting of the latter. When both stop valves in any 65 such branch are thus closed, it is also possible

to remove the interposed throttle valve for repair or replacement, the valves in one of the parallel branches 17 being thereupon opened so as to permit continuous operation of the pressure reducing step even while a worn valve is being thus replaced or repaired.

From header 18 the fluid is passed through the coil 21 which, as illustrated, is a pressure reducing coil of the type illustrated in Fig. 1, but which may be a labyrinth of the type illustrated in Fig. 2 or an equivalent 70 pressure reducing flow passage. Such coil may be heat insulated by means of an enclosing jacket 22 if desired. A series of tap lines 23 lead off from said coil at various 75 points in its length, such tap lines being joined to a header 24 and each being controlled by a throttle valve 25 with stop valves 26 on either side thereof, just as in the case 80 of the branches 17 that connect headers 16 and 18. By means of these taps, the passage of the fluid flow may be permitted 85 through the entire pressure reducing coil or labyrinth 21 or only a part thereof as may be desired.

If the fluid is cold and no vapor is to be conserved, the header 24 may be discharged directly by way of a pipe 27 into a receiver 28, but if at the temperature involved, vaporization takes place when pressure is reduced, preliminary separation may be made in a vapor separator 29 that drains through a cooler 30 into said receiver 28 and the hot vapor may then be condensed in whole or in part in a condenser 31 that drains into another receiver 32, the non-condensed vapors or gases being allowed to escape to waste or other use through a vent 33.

If a hot fluid be released through the apparatus just described, partial vaporization will occur with reduction of pressure provided the temperature is high enough. In such case, the volume of flow in the pressure reducing device 21 will increase with such vaporization and such increased volume will require less length of tube or a less number of restrictions satisfactorily to reduce the pressure in the apparatus to a point where the control valves 19 in the branches 17 of the supply line, or the corresponding valves 25 in the taps 23 to the discharge line, will satisfactorily throttle the flow and maintain a constant and desired pressure in the apparatus in advance of the header 16. Just as in the case of the simpler form of apparatus illustrated in Fig. 1, these control or throttling valves 19 and 25, either one or the other, or both, may be automatically controlled if desired.

The general layout of elements arranged as shown in Fig. 3 also permits in certain processes of the economic use of the heat in a processed liquid to evaporate a portion of the same and thus save heat which would otherwise be required if vaporization were 125 130

necessary in the process. There is also provided a method of separating such liquid into two or more constituents by means of the mechanical separator and condenser provided for the vapor, as described above. If the condenser be worked to condense all the vapor, two fractions are obviously secured, while if it be worked to condense only a part of such vapor, a third fraction will leave through the vent 33 and if of value may of course be recovered by being separately condensed. This principle of operation may be elaborated upon to any desired degree by the interposition of additional condensers and separators, as will be readily understood.

In releasing a hot fluid it may alternatively be first cooled under pressure by interpolation of a cooler in the flow ahead of the pressure reducing device, or devices, without affecting the principle of my invention.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:—

30 1. A method of discharging a high pressure fluid from an autoclave, which comprises releasing such high pressure fluid through an orifice and simultaneously retarding the rate of flow thereof by causing the fluid stream to

35 traverse a constricted passageway of sufficient length to absorb by frictional resistance a material portion of the total pressure drop, whereby destructive action upon such orifice is reduced.

40 2. A method of releasing fluid from a higher to a lower pressure, which comprises controlling the rate of release by a controlled orifice responsive to such higher pressure, and progressively lowering the pressure of the fluid by passing it through an extended passageway offering resistance to flow therethrough in amount sufficient to limit the pressure drop in the controlled orifice to a minor fraction of the total pressure drop.

45 3. In apparatus of the character described, means for controlling the withdrawal of a fluid under high pressure from a container, said means comprising a valve and a passage offering high resistance to absorb a large portion of the pressure drop.

50 4. In apparatus of the character described, the combination of an autoclave, valve means for controlling the volume of a fluid stream passing from such autoclave, and means other than a valve for reducing the destructive action at said valve means by opposing resistance in an extended passageway.

55 5. In apparatus of the character described, the combination of an autoclave, valve means for controlling the volume of the fluid stream

passing from such autoclave, and means other than a valve to provide a sufficient resistance in the path of flow of such stream to materially absorb pressure drop, whereby destructive action on the valve is inhibited.

70 6. In apparatus of the character described, the combination of an autoclave, valve means for controlling the volume of a fluid stream passing from such autoclave, and means for reducing the destructive action at such valve, said means including a pressure-drop absorbing labyrinthine passageway.

75 7. In apparatus of the character described, the combination of an autoclave, valve means for controlling the volume of a fluid stream passing from such autoclave, and means for reducing the destructive action at such valve, said means including a pressure-drop absorbing adjustable passageway.

80 8. In apparatus of the character described, the combination of an autoclave, a branched discharge line, a control valve in each of the branches of said line, a stop valve on either side of each said control valve, and an extended passageway opposing straight-direction flow communicable with said branches.

85 9. In pressure relieving apparatus for autoclaves and the like, the combination of a branched discharge line, a control valve in each of the branches of said line, two stop valves in each such branch, one on each side of the corresponding control valve, and a header connecting such branches beyond said valves and leading to the discharge.

90 10. In pressure relieving apparatus for autoclaves and the like, the combination of a branched discharge line, a control valve in each of the branches of said line, two stop valves in each such branch, one on each side of the corresponding control valve, a header connecting such branches beyond said valves, and a duct leading from said header and including a portion arranged and constructed to interpose resistance to the flow of the fluid therethrough, whereby a substantial portion of the drop in pressure is absorbed.

95 11. In pressure relieving apparatus for autoclaves and the like, the combination of a branched discharge line, a control valve in each of the branches of said line, two stop valves in each such branch, one on each side of the corresponding control valve, a header connecting such branches beyond such valves, a duct leading from said header and including a portion arranged and constructed to interpose resistance to the flow of the fluid therethrough, whereby a substantial portion of the drop in pressure is absorbed, and a plurality of taps connected with said duct at different distances from said header.

100 Signed by me this 23rd day of September, 1925.

THOMAS GRISWOLD, JR.
